UNITED STATES PATENT OFFICE

148,712

DESIGN FOR A CLOTHESLINE PULLEY OR SIMILAR ARTICLE

Eugene Lorenz, Springfield, N. J.

Application September 4, 1946, Serial No. 133,049

Term of patent 3½ years

(Cl. D41—1)

To all whom it may concern:

Be it known that I, Eugene Lorenz, a citizen of the United States, residing in Springfield, in the county of Union, State of New Jersey, have invented a new, original, and ornamental Design for a Clothesline Pulley or Similar Article, of which the following is a specification, references being had to the accompanying drawing, forming a part thereof.

Fig. 1 is a perspective view of a clothes line pulley embodying my new design,

Fig. 2 is an end elevational view taken from the right of Fig. 1; and

Fig. 3 is a bottom plan view thereof.

I claim:

The ornamental design for a clothesline pulley or similar article, as shown.

EUGENE LORENZ.
